UNITED STATES PATENT OFFICE

150,391

DESIGN FOR A PIPE SMOKER'S STAND

William C. Zelle, St. Louis, Mo.

Application April 2, 1947, Serial No. 138,116

Term of patent 14 years

(Cl. D85—2)

To all whom it may concern:

Be it known that I, William C. Zelle, a citizen of the United States, and a resident of the city of St. Louis and State of Missouri, have invented a new, original, and ornamental Design for Pipe Smoker's Stand, of which the following is a specification, reference being had to the accompanying drawing, forming part thereof.

Fig. 1 is a front elevational view of a pipe smoker's stand, showing my new design.

Fig. 2 is a side elevational view.

Fig. 3 is a top plan view, showing the handle swung downwardly on one side of the stand; and

Fig. 4 is a bottom plan view.

I claim:

The ornamental design for a pipe smoker's stand, substantially as shown.

WILLIAM C. ZELLE.
